Primary Examiner — Rachel A. Voorhies*(74) Attorney, Agent, or Firm* — Vista IP Law Group, LLP**CLAIM**

The ornamental design for a display panel or portion thereof with a graphical user interface, as shown and described.

DESCRIPTION

The sole FIGURE is a front view of a display panel or portion thereof with a graphical user interface showing a design.

The broken line showing of a display panel or portion thereof with a graphical user interface is included for the purpose of illustrating portions of the article and forms no part of the claimed design. The remaining broken lines illustrate portions of the graphical user interface and the mixed reality environment, and form no part of the claimed design.
